THE NORRIS PETERS CO., PHOTO-LITHO., WASHINGTON, D. C.

UNITED STATES PATENT OFFICE.

WILLIAM JAMES ADAMS, OF COCHRANTON, PENNSYLVANIA, ASSIGNOR TO NONPAREIL MANUFACTURING COMPANY, OF COCHRANTON, PENNSYLVANIA.

MOTOR-STAND.

1,273,981.

Specification of Letters Patent.

Patented July 30, 1918.

Application filed July 7, 1917. Serial No. 179,226.

To all whom it may concern:

Be it known that I, WILLIAM JAMES ADAMS, a citizen of the United States, residing at Cochranton, in the county of Crawford and State of Pennsylvania, have invented a new and useful Motor-Stand, of which the following is a specification.

The subject of this invention is a motor stand wherein a motor holding frame is adjustably secured between supporting standards, and the objects of the invention are, first, to provide a motor support which may be adjusted to various positions, second, to provide a motor support with a frame within which a motor may be hung and means for adjusting the frame to various positions, third, to provide a motor supporting frame adjustably hung between standards and clutches for securing the frame in its adjusted positions, fourth, to provide means for adjusting the frame to various sizes of motor, fifth, to provide means for locking the side bars of the frame against turning, sixth, to provide means for readily transporting the frame with the motor supported therein to different parts of the shop, seventh, to provide a simple and efficient motor stand.

With the foregoing and other objects in view which will appear as the description proceeds, the invention resides in the combination and arrangement of parts and in the details of construction hereinafter described and claimed, it being understood that changes in the precise embodiment of the invention herein disclosed, can be made within the scope of what is claimed, without departing from the spirit of the invention.

A practical embodiment of the invention is shown in the accompanying drawings, wherein:

Figure 1 is a side elevation of the device. Fig. 2 is a top plan view of the device.

Fig. 3 is a central vertical cross section.

Fig. 4 is a detail sectional view taken on the line 4—4 of Fig. 2, parts being removed.

Fig. 5 is a detail showing an end bar of the adjustable frame in elevation.

Fig. 6 is a plan view of the same.

Fig. 7 is a detail sectional view on the line 7—7 of Fig. 6.

Fig. 8 is a detail perspective view of the end of one of the side bars of the frame.

Referring to the drawings by numerals of reference:

The stand is provided with the supporting legs 1, four being shown in the present instance, arranged in pairs at each end of the stand. At the lower ends of one pair of legs 1 are mounted brackets 2—2 which turn on the legs but are normally held against turning by the pins 3 on which are threaded nuts 4. Journaled in the end of each bracket 2 is a roller 5. The object of this construction is to allow the stand to be raised at one end, the legs being used as handles, and propelled from one location to another on the rollers 5. Each pair of legs 2 is tied together at a median point by an angle plate 6 which is secured to the legs by bolts 7, or otherwise. The tops of each pair of legs are joined by a tie plate or casting which is formed with an angularly disposed upper flange or top 8 preferably formed with circular ends as shown which are adapted to seat upon the upper ends of the legs 1, and with curved ends 9 which form grooves for the reception of the legs 1. This tie plate is secured in place on the legs by bolts 10, or otherwise. Each tie plate is formed with a centrally disposed, laterally extending boss 11, which may be integral with the plate or attached thereto, and which is formed with an annular rib or tongue 12 and a central bore 36. Each boss forms a member of a clutch which will be hereinafter explained. The pairs of legs are bound together by tie bolts 13 which pass through apertures formed in the vertically disposed portion of each angle plate 6 and which are surrounded by spacing sleeves or tubes 14.

A frame is adjustably rovolute within the support just described, and this frame is composed of end bars each of which is formed of a central channel bar 15 in the longitudinal channel of which slide the end members 16. Each member 16 is formed with a longitudinal slot 17 through which passes the shank of a set screw 18 which is threaded to engage a threaded aperture 19 formed in the channel bar 15. This set screw serves to adjustably secure the end members to the channel portion. On the inner face of the free end of each end member 16 is a circular boss 20 through the center of which and its end member extends a bore 21. Extending from each boss 20 to

ward the inner end of the end member, is a longitudinal rib 22. The rib 22 is adapted to take into a notch 23 formed in the end of each tubular side bar 24. The side bars 24 are bound in place between the end bars by tie bolts 25 which extend through the bores 21 and the bores of tubular side bars and are bound in place by nuts 26 which are threaded on the ends of the bolts. The side bars 10 as will be apparent, are held against turning on the bosses by the ribs 22 which engage the notches 23 as just described.

On each side bar 24 are adjustably secured inwardly projecting arms 27 each of 15 which is provided at one end with a hub 28 through which the side bar 24 passes. A set screw 29, passing through the hub, serves to clamp each arm 27 in place, when adjusted. A clamping plate 30 is pivoted on 20 each arm 27, and overlies a portion of the same and may be clamped upon the arm by a set screw 31. A boss 32 may be formed on each arm 27 and underlie the outer end of the plate 30 to place the plate in proper 25 position to be clamped.

The method of adjustably mounting this frame within the support is as follows:

Each channel bar 15 has secured to its outer face, by rivets, or otherwise, a boss 33 30 which is formed with an annular tapering groove 34 adapted to receive with close binding fit the annular tongue 12. Each boss 34 is formed with a central bore which is tapped to receive the threaded end of a hand 35 screw 35 which passes through a bore 36 formed through the center of each boss 11 hereinbefore mentioned. The hand screw 35 is formed with an enlarged cylindrical head 37 the inner end of which is adapted 40 to abut the outer face of the top tie plate or casting. A cross bar 40 is suitably secured to the head 37 and serves as a handle by which the hand screw 35 may be turned.

From the foregoing it will be seen that 45 the supporting arms 27 may be adjusted to accommodate motors of various lengths; that the side bars may be adjusted toward or away from each other to receive motors of various widths; that the frame may be 50 revolved to any position and there held to permit work on any part of the motor; and that the legs at one end of the stand may be grasped near the bottom and elevated so that the device will be supported on the rollers 55 5 when the stand may be easily moved from place to place about the shop.

In practice the device is used as follows:

The device being set up, a motor 41, indicated in dotted lines Fig. 3, may be put in place by turning the plates 30 to one side, 60 placing the motor within the frame with the flange between the motor proper and the crank case resting upon the arms 27; turn clamping plates 30 into position resting upon the flange at the thick part where bolts go through and clamp down with set screws; adjust the frame to any desired position by turning the hand screws 35 to release the clamps, and when the frame is adjusted to the desired position again turning the 70 hand screws 35 to engage the clamps.

Having described the invention, what is claimed as new and sought by Letters Patent is:

1. In a motor stand, a frame comprising 75 tubular side bars provided with a notch in each end, adjustable end bars, a boss on each end of the end bars and adapted to enter the bore of the side bars, a rib extending longitudinally of each end bar and adapted to 80 enter the notch, and means for clamping the side bars between the end bars, means for securing a motor within the frame, a support, and means for adjustably securing the frame to the supports. 85

2. In a motor stand, a frame comprising 90 side bars provided with a notch in each end, end bars, a rib on each end bar and adapted to enter the notch, and means for clamping the end bars to the side bars, means for securing a motor within the frame, a support, and means for securing the frame to the support. 95

3. In a motor stand, a frame comprising 100 side bars provided with a notch in each end, end bars, a rib on each end bar and adapted to enter the notch, a clutch element on each end bar, and means for clamping the end bar to the side bars, means for securing a motor within the frame, a support, clutch 105 elements on the support, and adapted to engage the clutch elements on the end bars of the frame, and means for drawing the clutch elements into contact to hold the frame in adjusted position within the support. 105

In testimony that I claim the foregoing as my own, I have hereto affixed my signature in the presence of two witnesses.

WILLIAM JAMES ADAMS.
